[57] **CLAIM**

The ornamental design for a component mounting plate for a PC board indicator and control device, substantially as shown and described.

DESCRIPTION

FIG. 1 is a perspective view of a component mounting plate for a PC board indicator and control device according with my new design;

FIG. 2 is a top plan view of the indicator and control device shown in FIG. 1;

FIG. 3 is a bottom plan view of the indicator and control device shown in FIG. 1;

FIG. 4 is a right side elevational view of a indicator and control device shown in FIG. 1, the left side elevational view being identical thereto; and

FIG. 5 is an elevational view of the indicator and control device shown in FIG. 1, the rear end elevational view being identical thereto.
